UNITED STATES PATENT OFFICE.

MAURICE NEUMAN, OF CHICAGO, ILLINOIS.

TOBACCO-PIPE.

1,107,988.

Specification of Letters Patent. Patented Aug. 18, 1914.

Application filed September 23, 1913. Serial No. 791,320.

To all whom it may concern:

Be it known that I, MAURICE NEUMAN, a citizen of the United States, and a resident of Chicago, in the county of Cook and State 5 of Illinois, have invented an Improvement in Tobacco-Pipes, of which the following is a specification.

My present invention relates to tobacco pipes and my object is to provide a pipe 10 embodying certain novel parts, arrangements of parts and adjustments whereby the quantity and temperature of the smoke may be regulated to suit the user, whereby to eliminate in a great measure the production 15 of nicotine, and whereby certain other advantages to the smoker may be promoted and attained. These parts, arrangements of parts, and adjustments together with their resulting advantages will be more clearly 20 understood from the following description thereof, reference being made to the accompanying drawing, in which—

Figure 1 is a vertical longitudinal section, taken centrally through the pipe. Fig. 2 is 25 an elevation of the bowl and stem. Fig. 3 is a top plan view of the rotatable bowl ring. Fig. 4 is a transverse vertical section through the stem looking toward the bowl. Fig. 5 is a detail horizontal section taken 30 on line 5—5 of Fig. 1. Fig. 6 is a top plan view of the rotatable tobacco receptacle. Fig. 7 is a bottom plan view of the ring shown in Fig. 3. Fig. 8 is a detail transverse section through the stem, taken on line 8—8 35 of Fig. 1, and, Fig. 9 is a similar view taken on line 9—9 of Fig. 2.

Referring now to these figures, the bowl A is provided with the usual curved main stem B and mouthpiece C, and is also provided 40 with a smoke stem D connecting the bowl adjacent its upper end with the upper end of the main stem B, the latter being without the usual smoke passage and having instead a groove b the outer portion of 45 which is covered by a curved cover plate B'.

The bowl A is of a substantial length and has a deep opening or bore, the upper end of which is enlarged to provide an annular shoulder on which the annular flange e of 50 the tobacco chamber or receptacle E rests, the lower body of this receptacle being snugly though movably fitted with the bore of the bowl.

Rising from a point intermediate the inner and outer edges of the flange e is the 55 upper wall e' of the receptacle E and rest-

ing upon the inner portion of the flange within this wall is the lower reduced edge of the rotatable bowl ring F, the upper portion of which is enlarged and seated on the upper end of bowl A. This ring is provided with a plurality of recesses f in its lower edge which receive projections e² of the flange e and through which extend fastening members f' (see dotted lines in Fig. 1) 60 for securing the ring F to the receptacle E. The ring F is also provided with a circular series of openings f² adjacent its lower edge which are alined with similar openings through the upper receptacle wall e'. 65

The receptacle E and ring F are held down in place by means of a split collar G surrounding the wall e' and resting on the outer edge of flange e, and secured to the bowl A by a fastener g and additionally held by a coil spring g' bearing thereagainst and surrounding the mouth of the smoke tube H, which mouth or inner end of said smoke tube extends through an opening in the split collar G and is adapted to register with the several ring openings f². To the end that an unobstructed smoke passage may be maintained at all times the ring F has a series of index marks f³ upon its upper surface above its openings f², any one of which 70 may be turned to a position centrally of the supplemental stem D in order to register a selected ring opening f² with the mouth of the smoke tube H, the latter extending through the supplemental stem and through 75 transverse openings in the outer end of the main stem B and the lower reduced end of the mouthpiece C, thus locking the latter in 80 position.

The outer end of the smoke tube H is 85 closed by a screw cap or plug h which may be removed to provide for the introduction of any instrument for cleaning purposes.

In the receptacle E is a vertically adjustable base E' which may be easily adjusted by means of a slide arm I curved to fit and move longitudinally within the groove b of the main stem B, the inner cam-shaped end of this slide arm being extended beneath the base E'. The outer end of the 90 slide arm I has a knob or button i projecting through and working in a slot at one side of the cover plate B' as shown in Fig. 4, and the intermediate portion of the arm has a longitudinal guide slot i' through 95 which projects one of the cover plate fasteners b' around which is secured one end 100 105 110

of a curved spring I', the free end of which bears against the slide arm to hold the same in adjusted position.

The mouth-piece C communicates with 5 the smoke passage H through an opening h' in the wall of the latter and thus with the parts in the position shown in dotted lines in Fig. 1, the receptacle E may be filled and the tobacco lighted as in the ordinary 10 pipe. As soon as the operation is well started, the quantity of smoke may be quickly and easily regulated and the consumption rendered uniform by rotating the ring F to desired points and the temperature 15 may be controlled by raising or lowering the base E'. These adjustments, it will be noted, may be readily and quickly made and the entire operation controlled to suit the needs or peculiar tastes of the user.

20 It is to be further noted that the smoke is withdrawn from the bowl without necessitating its passage through the bulk of tobacco within the tobacco receptacle, thus 25 eliminating in a great measure the production of nicotin.

I claim:—

1. A tobacco pipe comprising a bowl, a curved main stem extending upwardly from the lower end of the bowl, a mouthpiece 30 connected to the stem, a supplemental stem connecting the upper portions of the bowl and main stem and having a smoke passage communicating at one end with the bowl and at its opposite end with the mouthpiece, 35 a rotatable tobacco receptacle within the bowl, a ring seated on the upper end of the bowl and connected to the receptacle, a vertically adjustable base within the receptacle, and a member slidably mounted in the 40 main stem for adjusting the said base.

2. A tobacco pipe comprising a bowl, a curved main stem extending upwardly from the lower end of the bowl, a mouthpiece having its lower end extended into the upper 45 end of the main stem, a supplemental stem connecting the upper ends of the main stem and bowl, said main stem and said mouthpiece having transverse aligned openings, and a smoke tube extending through the 50 supplemental stem and communicating at one end with the bowl and having its opposite end extending through the transverse openings of the main stem and mouthpiece, and provided with a wall opening communicating with the mouthpiece.

3. A tobacco pipe comprising a bowl, a

smoke stem communicating with the upper portion of the bowl, a mouthpiece communicating with the stem, a rotatable tobacco receptacle within the bowl and having a 60 vertically adjustable base, a ring seated on the bowl and connected to the tobacco receptacle for rotating the latter, and means for adjusting the base.

4. A tobacco pipe comprising a bowl a 65 smoke stem communicating with the upper portion of the bowl, a mouthpiece communicating with the stem, a rotatable tobacco receptacle within the bowl and having a plurality of points of communication with the 70 smoke stem controlled by rotation of the receptacle, the bowl having a vertically adjustable base, and means for adjusting the base.

5. A tobacco pipe comprising a bowl, a 75 curved main stem extending upwardly from the lower end of the bowl and having a groove the lower end of which extends centrally into the base of the bore of the bowl, a mouthpiece connected to the upper end of 80 the stem, a supplemental stem connecting the upper portions of the bowl and the main stem and having a smoke passage communicating with the upper portion of the bore of the bowl and the lower end of 85 the mouthpiece, the bore of the bowl having an upper enlarged portion forming an intermediate annular shoulder, a tubular tobacco receptacle rotatable within the bowl bore and having an upper outwardly projecting 90 flange seated on the said shoulder, a split clamping collar seated on the outer edge of the receptacle flange and secured to the bowl, a rotating ring seated on the upper end of the bowl and having a depending 95 reduced portion secured to the inner edge of the receptacle flange, said reduced ring portion also having a circular series of openings each of which may be positioned to register with the smoke passage, a base 100 plate vertically adjustable within the tobacco receptacle, and an arm slidably mounted in the main stem groove and having an inner cam-shaped end beneath the base plate and an exterior projecting 105 or handle upon its outer end, all for the purpose described.

MAURICE NEUMAN.
